CRAB BAIT CLAMP

Frederick A. Bornefeld, Jaynes Ave., Island Heights, N.J.

Filed Aug. 27, 1959, Ser. No. 57,343

Term of patent 14 years

(Cl. D17—3)

FIGURE 1 is a top plan view of a crab bait clamp, showing the new design.

FIGURE 2 is a front elevational view thereof, the rear elevation being the same.

FIGURE 3 is an elevational view of one end thereof.

FIGURE 4 is a bottom plan view thereof; and

FIGURE 5 is an elevational view of the other end thereof.

I claim:

The ornamental design for a crab bait clamp, as shown and described.
